UNITED STATES PATENT OFFICE.

CHARLES S. SHARP, OF AUBURN, NEW YORK, ASSIGNOR TO THE D. M. OSBORNE & COMPANY, OF SAME PLACE.

CORN-HARVESTER.

SPECIFICATION forming part of Letters Patent No. 614,062, dated November 8, 1898.

Application filed July 1, 1896. Serial No. 597,674. (No model.)

To all whom it may concern:

Be it known that I, CHARLES S. SHARP, of Auburn, county of Cayuga, State of New York, have invented an Improvement in Corn-Harvesters, of which the following description, in connection with the accompanying drawings, is a specification, like letters on the drawings representing like parts.

This invention relates to corn-harvesters of that class wherein the corn is cut and fed along a passage-way in upright position to a binder, which receives and binds it "on end," such a corn-harvester being shown in my United States Patent No. 539,830, dated May 28, 1895; and the invention has for its object to improve the construction of such a corn-harvester to the end that it may be regulated or adjusted for binding tall or short corn and also that short corn may be conveyed along the corn-passage to the binder without liability or tendency to fall in various directions—as, for instance, to one side of the passage-way.

To regulate the machine for binding tall or short corn, I herein vary the position of the bottom or deck of the binder relatively to the binder mechanism, and as said bottom or deck is held in different elevations it becomes necessary to also correspondingly adjust the bottom or floor of the corn-passage upon which the butts of the severed corn rest in order that the severed corn may be properly delivered to the binder. In carrying out this part of my invention I may and preferably do provide a bottom piece for the corn-passage, which extends from the cutting mechanism rearwardly to the binder and which is inclined upwardly from front to rear, and pivot said upwardly-inclined bottom piece at its forward end to the frame, adjacent to said cutting mechanism, and said upwardly-inclined bottom piece serves as the floor of the corn-passage, and said bottom piece is continued rearwardly beyond the rear end of the corn-passage, and such continuation thereof serves as the bottom or deck of the binder, and the rear end of said bottom piece rests upon or is supported by an adjustable support, by means of which it may be raised and lowered on its pivotal connections and held in different elevations. In a machine of this

kind it is common to employ upper and lower feeding devices for the corn, the upper feeding devices engaging the stalks of corn quite a distance above the butts and the lower feeding devices engaging the corn at or near the butts, and as the corn is usually quite tall said upper feeding devices are arranged to work quite a distance above the lower or butt-feeding devices. In a field short corn frequently appears mixed with the tall corn and sometimes all the corn in the field is quite short, and in either case the upper feeding devices when arranged to act properly on the tall corn will not engage the short corn, and as a result said short corn when held only by the butts will soon topple over.

In order that short corn may be conveyed along the corn-passage to the binder without falling in different directions, means are here provided which engage the stalks of such short corn some distance above the butts, which hold such corn in upright position as it is fed along. In carrying out this part of my invention a pair of stalk-engaging arms, preferably made spring-actuated, are located beneath the upper feeding device and one at each side of the corn-passage, and they are attached at their forward ends and project rearwardly toward the binder and also project more or less into the corn-passage, at opposite sides thereof, and by their spring action normally press one against the other. As the upright corn passes between these arms they bear upon or against the stalks and assist in holding the corn in upright position as it is fed along to the binder and until caught by the packers. In case the corn congregates in the corn-passage these arms will act to separate the stalks, with a tendency to deliver them to the binder in single file.

Figure 1 shows in plan view a corn-harvester embodying this invention; Fig. 2, a vertical longitudinal section of the corn-harvester shown in Fig. 1, taken on the dotted line *x x*; Fig. 3, a horizontal section of the corn-harvester taken on the dotted line *y y*, Fig. 2; Figs. 4 and 5, details showing the adjustable or pivoted bottom piece for the corn-passage and binder and means for adjusting it to different elevations; Figs. 6 and 7, details showing an adjustable connection for

the stalk-engaging arms which assist in holding the short corn and in delivering it in single file to the binder.

The gathering-arms, consisting of the upper inclined portions a b and lower horizontal portions arranged beneath them, are supported by the framework and adapted to form a more or less laterally-confined passage-way extending from the forward end of the machine rearwardly toward the binder, which may be of any suitable construction. A cutter d^{16} crosses this passage-way a suitable distance back of its forward end, which severs the corn that is gathered by the gathering-arms and which is presented to it. The feeding devices herein shown for feeding the corn along the laterally-confined passage-way consist of an upper or stalk feeding device a^5 , which comprises a pair of feeding-chains moving in parallelism with the upwardly-inclined portions a b and a lower or butt feeding device which comprises a set of reciprocating toothed plates c .

So much of the corn-harvester herein shown and which it appears necessary to refer to is substantially the same as in United States Patent No. 539,830, heretofore referred to, to which reference may be had.

A bottom piece is provided which extends from the cutting mechanism d^{16} rearwardly to the rear of the binder, said bottom piece being bent transversely at an angle substantially midway its length, presenting forward of said bend an upwardly-inclined portion c^2 , which extends from the cutting mechanism d^{16} rearwardly to the binder and which serves as a bottom piece or floor for the lower end of the corn-passage and presenting at the rear side of said bend a substantially horizontal portion c^3 , which serves as a bottom deck or floor for the binder. The portion c^2 of the bottom piece, which serves as the floor of the corn-passage, inclines upwardly from front to rear—i. e., from the cutter d^{16} to the binder—and the portion c^3 of said bottom piece, which serves as the deck of the binder, forms a continuation of said upwardly-inclined floor c^2 . This bottom piece c^2 c^3 is pivoted at its forward end, as at c^4 , to the frame adjacent to said cutting mechanism d^{16} , any usual or suitable pivot or hinge connection being employed. The rear end of said bottom piece c^2 c^3 rests upon and is supported by an arm c^5 , which is secured to and projects rearwardly from a rock-shaft c^6 , having its bearings in the frame. An operating lever or arm c^7 is secured to said rock-shaft c^6 , by means of which it may be turned to raise and lower the arm c^5 , and thereby vary the height of the rear end of the pivoted bottom piece.

The segment c^8 is secured to the frame, having several holes c^9 , and on the lever c^7 a lug c^{10} projects inwardly, which is made of such size as to fit the holes in said segment and so disposed as to enter any one of said holes as the lever is turned.

A spring c^{12} encircles the rock-shaft c^6 and

is connected with the lever in such manner as to draw said lever toward the segment in order that its lug may be held in one of the holes. To disengage said lever, it will be pressed or moved laterally and when so disengaged may be turned, as desired, to rock the shaft c^6 .

It will be seen that the arm c^5 , of which there may be one or more, as desired, and the rock-shaft and means for operating it constitute an adjustable support for the rear end of the pivoted bottom piece.

In Fig. 4 the pivoted bottom piece is represented in three different positions, thereby enabling short and tall corn to be bound in a like manner.

I do not desire to limit my invention to the particular construction of means employed for operating the pivoted bottom piece, as it is obvious that it may be moved or turned on its pivotal connections in many different ways, all of which come within the spirit and scope of this invention; but I find that an adjustable support for the rear end of said pivoted bottom piece is efficient and enables the results sought for to be practically carried out. Nor do I desire to limit my invention to forming the bottom piece in a single piece and serving as a floor for the corn-passage and a deck for the binder; but in practice it is much better to adjust the floor of the corn-passage and deck of the binder simultaneously, and hence said floor and deck may be connected together or formed in a single piece. By adjusting the floor of the corn-passage from the cutting mechanism rearwardly to the binder the degree of ascent will be but slightly changed to compensate for a material change in location of the deck of the binder.

A pair of corn-engaging arms a^{50} are located beneath the upper feeding device, they being attached at their forward ends, respectively, to the under sides of the arms a b and extended rearwardly toward the binder, their rear ends terminating adjacent the needle or packer of the binder, and said rear ends of the arms are free or unattached. The rearwardly-extended arms a^{50} , located close to the corn-passage, one at each side thereof, also project more or less into or partially across said corn-passage, as shown in Fig. 1, and as they occupy the same plane they will therefore bear against each other. These corn-engaging arms a^{50} may be made as flat or leaf springs—i. e., of flat spring-metal bars—and attached at their forward ends to the arms a b , and they thus resemble a pair of long slender flat springs projecting rearwardly toward the binder and more or less into the corn-passage, bearing against each other with a pressure due to their own spring action. In lieu of thus making said corn-engaging arms a^{50} as flat springs or flat spring-acting strips of metal, they may be made of wood and connected to the frame by spring-hinges or in any other desirable way, so long as they subserve the desired ends. These corn-engaging

arms a^{50} are provided especially for the purpose of holding up short corn as it is conveyed along the corn-passage and which if quite short will disengage the upper feeding device, 5 and hence they are so disposed as to engage the stalks of corn some distance above the butts.

I am aware that a pair of spring-arms have been employed which engage the butts of the 10 corn and assist more or less in guiding the corn as it is fed along; but the arms a^{50} herein shown differ essentially from said butt-guide arms in that they perform an entirely different function—viz., by engaging the stalks of 15 corn some distance above the butts they assist in holding in upright position short corn. These corn-engaging arms also possess another quite important function—i. e., they act to regulate the delivery of the corn to the 20 binder—as, for instance, suppose the corn should be more or less congregated in the corn-passage, moving along in bunches, it will be seen that as it passes between said corn-engaging arms it will be more or less 25 separated by reason of the continuous pressure exerted thereon by said arms, and as a result the corn will be caused to pass along in single file or in a more regular order. I 30 may employ several pairs of such arms, if desired.

Referring to Figs. 6 and 7, an adjustable connection is shown by which these corn-engaging arms a^{50} are adjustably attached to the under side of the arms $a\ b$. a^{51} represents a flat base of a casting, and a^{52} a projection thereon. The base a^{51} has a hole a^{53} at one end, through which passes the pivot-bolt by means of which the casting is pivotally connected to the arm, and said base a^{51} has a 40 curved slot a^{54} , through which passes an adjusting-bolt, and said base is held securely to the arm by tightening the nuts of both the pivot and adjusting bolts. This casting a^{51} is thus securely held in position, yet capable 45 of adjustment in a more or less horizontal plane, and serves as a support for the arm a^{50} , which is attached to it, as will be described, and by the adjustment above described said arm is moved in and out. The projection a^{52} 50 on the casting a^{51} has a hole which receives the pivot-bolt of the arm a^{50} and has also a curved slot a^{55} , which receives an adjusting-bolt which passes through said corn-engaging arm a^{50} , and said arm a^{50} is securely held in 55 place by tightening the nuts of said bolts, yet is capable of being adjusted up and down to act upon the corn at different elevations.

It will be observed that in the type of machine herein shown the binder-deck is elevated above the cutter, and the floor of the corn-passage from the cutter to the binder is inclined upwardly from front to rear, and that the feeding devices, by means of which the upright stalks of corn are conveyed along 60 said corn-passage, are also inclined upwardly from front to rear, substantially in parallelism with said floor, said upright stalks of corn

resting upon said floor, and in order to adjust said floor so that its rear end shall occupy different elevations to correspond to variations in the position of the deck of the binder and still permits said upwardly-inclined feeding devices to successfully operate and feed along the standing corn without materially increasing the draft and without stripping off the ears said floor is pivoted at its forward end immediately in rear of the cutter. By pivoting the floor at such point any movement thereof whereby its rear end may be adjusted to different elevations will but 70 slightly change its relative position to the upwardly-inclined feeding devices from end to end thereof and the draft will not be materially increased. Neither will the ears be stripped off, as the stalks move slowly perpendicularly relatively to the feeding devices 75 which engage them.

As heretofore stated, the corn-engaging arms possess the capability or function of holding short corn in upright position and 80 also of separating the congregated stalks, to thereby regulate the delivery of the stalks to the binder, and to enable said arms to better carry out this latter function—viz., to separate the congregated stalks—the feeding devices which feed the corn along the corn-passage are not only given a rearward movement, but also a lateral movement relative to the corn-passage, so as to engage the stalks of 85 corn and move them along and then disengage them.

I claim—

1. In a corn-harvester, a corn-passage extending from the cutter to the binder, upwardly-inclined feeding devices working rearwardly along said corn-passage, a floor for said corn-passage inclined upwardly from front to rear substantially in parallelism with said feeding devices and pivoted at its forward end directly in rear of the cutter, and means for adjusting said floor on its pivotal connection whereby its rear end may occupy different elevations yet its position relative to said feeding devices will be varied gradually from end to end thereof, substantially 100 as described.

2. In a corn-harvester, means for gathering and cutting the corn, a binder having a deck adjustable to different elevations above the cutter, a corn-passage extending from the cutter to said binder, having a floor inclined upwardly for its entire length, and pivoted at its forward end directly in rear of the cutter, means for moving said floor on its pivotal connection and for holding it in different elevations, and feeding devices moving in an upwardly-inclined plane corresponding to the upward inclination of said floor for feeding the severed corn in upright position along said corn-passage, substantially as described. 115

3. In a corn-harvester, means for gathering and cutting the corn, a binder having a deck elevated above the cutter, a corn-passage extending from the cutter to said binder having

- a floor inclined upwardly for its entire length and pivoted at its forward end directly in rear of the cutter, and connected at its rear end with said binder-deck, and means for adjusting said floor and binder-deck to different elevations, and feeding devices moving in an upwardly-inclined plane corresponding to the upward inclination of said floor, for feeding the severed corn in upright position along said 5 corn-passage to the binder, substantially as described.
4. In a corn-harvester, a corn-passage, upper and lower feeding devices for feeding the upright corn along to the binder, and one or 10 more corn-engaging arms a^{50} , located adjacent to the upper feeding device, which extend from a point forward of the rear of the upper feeding device rearwardly toward the binder and project more or less into said corn-passage and engage the corn some distance above the butts, substantially as described.
5. In a corn-harvester, a corn-passage, upper and lower feeding devices for feeding the upright corn along to the binder, and a pair 15 of corn-engaging arms located beneath and adjacent to the upper feeding device which extend rearwardly toward the binder, from a point forward of the rear of said upper feeding device, and which project more or less 20 into the corn-passage at opposite sides, substantially as described.
6. In a corn-harvester, a corn-passage, upper and lower feeding devices for feeding the upright stalks along to a binder, and a pair 25 of corn-engaging arms located beneath the upper feeding device which extend rearwardly toward the binder and project more or less into the corn-passage at opposite sides and engage the corn some distance above the 30 butts and terminate beyond the rear ends of the upper feeding devices and within the path of the packers, substantially as described.
7. In a corn-harvester, a corn-passage, upwardly-inclined feeding devices for feeding 35 upright corn along to the binder, and a pair of spring-arms attached to the frame beneath yet adjacent to said upper feeding device, one at each side of the corn-passage, which extend rearwardly toward the binder, and project more or less into the corn-passage to bear 40 against the corn and assist in holding the corn in upright position as it is fed along the corn-passage to the binder, substantially as described.
8. In a corn-harvester, a corn-passage, a cutter, an upwardly-inclined feeding device which engages the corn in front of and also at the rear of the cutter, a butt-feeding device working at the rear of the cutter, and a 45 pair of corn-engaging arms a^{50} , located beneath but adjacent to said upwardly-inclined feeding device, which extend rearwardly from a point in front of the rear end of said feeding device, substantially as described.
9. In a corn-harvester, a corn-passage, corn-holding arms a^{50} , supports therefor to which

they are pivotally connected, and means for adjusting said arms on their pivots up and down and holding them in different elevations, substantially as described.

10. In a corn-harvester, a corn-passage, corn-holding arms a^{50} , supports to which they are attached, and means for adjusting said supports on their pivots to thereby move said arms in and out, substantially as described.

11. In a corn - harvester, a corn - passage, arms a, b , at the sides thereof, and stalk-holding arms a^{50} attached to the under sides of said arms a and b , extending rearwardly toward the binder and more or less inwardly toward each other, and means for adjusting said arms a^{50} independently up and down and in and out, substantially as described.

12. In a corn - harvester, a corn - passage along which the severed corn is fed in upright position, a pair of yielding corn - engaging arms located one at each side of said corn-passage and projecting more or less thereinto, and which act upon the corn above the butts as it is fed along said corn-passage, to more or less separate the congregated stalks of corn and thereby regulate the delivery thereof, and feeding devices for feeding the severed corn along said corn - passage and between said corn-engaging arms having a rearward and a lateral movement, substantially as described.

13. In a corn - harvester, a corn - passage along which the severed corn is fed in upright position, a pair of corn-engaging arms, located one at each side of said corn-passage, and attached at their forward ends and left free or unattached at their rear ends, said arms projecting rearwardly and more or less into the corn-passage, and acting upon the corn some distance above the butts to separate the congregated stalks of corn, and feeding devices for feeding the severed corn along said corn-passage and between said corn - engaging arms having a rearward and a lateral movement, substantially as described.

14. In a corn-harvester, a cutter, a passage along which the severed corn is fed in upright position, a pair of corn-engaging arms located one at each side of said corn-passage, and attached at their forward ends and left free or unattached at their rear ends, said arms projecting rearwardly and bearing against each other at their rear ends and acting to separate the corn and thereby regulate its delivery, and feeding devices for feeding the corn along said corn-passage and between said corn-engaging arms having a rearward and a lateral movement, substantially as described.

15. In a corn - harvester, a corn - passage along which the severed stalks of corn are fed in upright position, a binder at the rear of said corn - passage, a pair of corn - engaging arms which act upon the corn in said corn-passage just in front of the binder, and separate congregated stalks, and feeding devices having a rearward and a lateral movement which engage the corn while acted upon by said corn-

engaging arms, and which move the corn along toward the binder into the path of the packers, substantially as described.

16. In a corn - harvester, a corn - passage along which the severed stalks of corn are fed in upright position, a binder at the rear of said corn-passage, a pair of coöperating corn-engaging arms constructed and arranged to act upon the corn which is moving along said corn-passage some distance above the butts, to separate congregated stalks, and to also hold up the short stalks of corn, and feeding devices having a rearward and a lateral movement, which intermittently engage and move rearward the corn, substantially as described.

17. In a corn - harvester, a corn - passage along which the severed stalks of corn are fed in upright position, means for separating congregated stalks of corn while moving along said corn-passage, and feeding devices having a rearward and a lateral movement, substantially as described. 20

In testimony whereof I have signed my name to this specification in the presence of two subscribing witnesses.

CHARLES S. SHARP.
